(57) CLAIM

We claim the ornamental design for the water dispensing unit, as shown and described.

DESCRIPTION

FIG. 1 is a perspective view of a water dispensing unit showing our new design;

FIG. 2 is a top plan view thereof.

FIG. 3 is a front elevation view thereof.

FIG. 4 is a bottom plan view thereof.

FIG. 5 is a right-side elevation view thereof.

FIG. 6 is a rear-side elevation view thereof; and,
FIG. 7 is a left-side elevation view thereof.

The broken lines are for illustrative purposes only and form no part of the claimed design.
